UNITED STATES PATENT OFFICE

2,504,893

POSITIONING AND SUPPORTING DEVICE
FOR CAR COUPLERS

Vinton E. Sisson, Chicago, Ill., assignor to Standard Railway Equipment Manufacturing Company, Chicago, Ill., a corporation of Delaware

Application October 31, 1946, Serial No. 706,986

4 Claims. (Cl. 213—61)

1

This invention relates to coupler supporting and positioning devices for railway car couplers, and more particularly to means to swingably and resiliently support a railway car coupler in such manner that when the coupler is uncoupled, said coupler is maintained by the device in substantially the longitudinal central plane of the car, or in what is known in the trade as "coupling range."

More specifically the device comprises a coupler carrier pivotally supported at its end by links which are pivotally, swingably, resiliently, and preferably adjustably supported intermediate their ends, from a member adapted to be fixed to a railway car, such as a striking casting, as shown in the drawings. To provide such a device for so supporting a coupler and maintaining it when uncoupled within said "coupling range" is the principal object of the invention.

Broadly, such a device is shown and claimed in my copending applications, Serial No. 706,982; Serial No. 706,983; Serial No. 706,984, and Serial No. 706,985, and the claims herein are accordingly restricted to the invention illustrated and described herein.

Another object of the invention is to provide such a cushioned coupler support and positioning device wherein should the cushioning means fail for any reason the device would nevertheless function as a coupler support and positioning device. In other words, should a spring break the coupler would still be swingably supported and be returned to "coupling range" by the device.

A further object of the invention is to provide such a cushioning coupler carrier and positioning device of the swing motion type wherein the cushioning means is not distorted during the swinging of the device.

A still further object of the invention is to provide such a cushioned coupler carrier and positioning device wherein provision is made for adjusting the height of the carrier and thereby the coupler to be supported thereby above the top of the rail without affecting the resiliency of said cushioning means.

The term "resilient means," as used in the specification and claims, is intended to cover springs, rubber or any other resilient material. Most of these materials, if intermittently compressed to excess progressively lose their effectiveness, and, consequently, it is a further object of the invention to provide means to limit the compression of said resilient means.

2

In the drawings:

Figure 1 is a half section, partly in elevation, on line 1—1 of Figure 2.

Figure 2 is an end view of the device.

Figure 3 is a view similar to Figure 1 with the coupler moved laterally.

Figures 4, 5, 6 and 7 are, respectively, top plan, side view, end view, and section on line 7—7, Figure 4, of the trunnioned support for the device.

Figures 8 and 9 are, respectively, plan and side views of the spring cap.

Figures 10 and 11 are, respectively, plan and side views of the spring seat.

Figures 12, 13 and 14 are, respectively, end view, side view and section on line 14—14, Figure 12, of the coupler carrier links.

Figure 15 is a top plan view of one end of the coupler carrier.

Figure 16 is a view similar to Figures 1 and 3 showing the device as it would appear without the cushioning means, yet still functioning as a coupler support and positioning device.

The device comprises a pair of spaced plates 1 and 2, maintained in spaced relation by webs 3 and 4 extending between said plates and either cast integral therewith or welded thereto as preferred. Plates 1 and 2 are of rectangular form, each having a central rectangular opening 5 therein, through which extends the shank 6 of the coupler, which is longitudinally, laterally and vertically movable therein, as is common. Web 4 is continuous from substantially side to side of the device adjacent the bottom thereof, whereas web 3 extends about the upper edge and down the sides about half way to the openings 5, and then turns laterally to form flanges or shelves 7, which are bifurcated at their ends. Each bifurcated end portion is formed into a pair of half bearings 8 adapted to receive the trunnions 9 of the spring seat supporting member, the central portion of which is upset and provided with an elongated rectangular eye 10, the elongation being at right angles to the axis of the trunnion.

Upon this trunnion support member rests the annular spring seat 11, it also having an elongated hole 12 therethrough. The upper surface of spring seat 11 is recessed so as to receive the lower convolution of the coil spring 13, upon which rests the spring cap 14, also annular in form and provided with an axial hole 15. The supporting link for each side of the device is shown at 16 and comprises a link-like member having a T-shaped head providing oppositely

extending trunnion portions 17-17, the other end of said link being screw-threaded, as at 18. Approximately midway between the ends of the link, the link is upset forming a pair of lateral shelf-like portions 19, extending from opposite sides of the link. The link is positioned between the spaced bearings 8 of flange or shelf 1, and trunnioned member 9 is slid down thereover until it passes portions 19 and trunnions 9 rest within the bearings 8. The spring seat 11 is also slid down on link 16 until opening 12 passes portions 19 when it is given a 90° turn so that if the spring breaks, portions 19 will then rest upon the spring seat and maintain the device in position to at least support and position the coupler. This possibility of the spring being broken and lost is illustrated in Figure 16, showing that the device would nevertheless still function as a coupler support and positioning device. Integral lugs 30 are formed on spring seat 11 so as to project within the ends of opening 10 and thereby hold said spring seat from accidentally rotating.

A nut 20 is applied to the screw threaded end of the link 16 to hold the parts in their assembled relation and to provide adjustment for the device.

The coupler carrier is shown at 21 and is installed between the striker walls 1 and 2 and extends from side to side thereof just above the web 4, and is designed to support the coupler 6. The ends of the coupler support 21 are bifurcated so as to straddle the shank of link 16, and each prong 22 thereof is formed with a concaved bearing portion designed to rest upon one of the tapered trunnions 17 and be resiliently supported thereon, which support will permit lateral angling of the coupler and its support 21. Depending reinforcing webs 23 are provided on opposite sides of the carrier to strengthen the same, and similarly upstanding webs 24 are provided on opposite sides of the coupler shank, said webs 24 occurring in plane with the walls of the bifurcation. (See Fig. 15.) Thus webs 24 insure that the carrier moves laterally with the coupler during any lateral angling thereof. Consequently, when the coupler 6 moves laterally the carrier 21 will be carried therewith causing the links 16 to swing on the bearings of prongs 22, and since the carrier is supported through the springs 13, the coupler is cushioned on its support, and the springs absorb all ordinary road shocks.

The size and tension of the spring is such as to hold the weight of the coupler and carrier in a position approximating that shown in Figure 1, with the lateral portions 19 of the link about one-half inch above the spring seat 11 which acts as a stop in cases when abnormal road shocks would draw the coupler and carrier down until portions 19 contacted the seat 11. This contact or stopping of further downward movement saves the spring from abnormal compression and enhances its life materially.

The accompany drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a device to swingably and resiliently sup-

port a coupler carrier from a member adapted to be fixed to a car and provided with spaced bearings at each end of said member, a trunnioned support adapted to be pivotally supported by said bearings at one end of said member, a seat resting upon said support, resilient means upon said seat, a cap upon said resilient means, a link passing between said bearings, through said support, said seat, said spring and said cap, and having pivotal connection with an end of a coupler carrier, and means for holding said cap, resilient means, seat and support in operative relationship.

2. Means to swingably and resiliently support a coupler carrier from a member adapted to be fixed to a car and provided with spaced bearings at each end of said member, said means comprising trunnioned supports, each of said supports being adapted to be pivotally supported by respective bearings at each end of said member, a spring seat resting upon each support, resilient means upon each seat, a spring cap upon each resilient means, a link passing between each of said respective bearings, through each of said supports, seats, springs and caps respectively, and having pivotal connection with an end of a coupler carrier, a stop on each of said links adapted to engage its respective seat to limit the compression of its respective resilient means without affecting the swingable support of said carrier, and means for holding said cap, resilient means, seat and support in operative relationship.

3. In a device to swingably and resiliently support a coupler carrier from a member adapted to be fixed to a car and provided with spaced bearings, a link extending between said bearings and, adapted to swingably suspend said carrier from said member about said link and, a trunnioned supporting member, adapted to be supported in said spaced bearings a cap on the upper end of said link, and resilient means about said link and, interposed between said cap and said supporting member, to resiliently suspend said carrier, whereby said carrier may move vertically and laterally with said coupler.

4. In a device to swingably and resiliently support a coupler carrier from a member adapted to be fixed to a car and provided with spaced bearings at each end of said member, a link pivotally connected to one end of said carrier and passing between said bearings, a trunnioned support having an opening therethrough through which said link extends, and adapted to be pivotally supported by said bearings, a seat about said link and resting upon said support, a cap adjustably mounted upon said link, resilient means about said link, between said seat and cap, and means on said link normally held by said resilient means in spaced relation from said seat to limit the compression of said resilient means without affecting the swingable support of the carrier.
